UNITED STATES PATENT OFFICE.

SIEGFRIED G. MARSHUTZ, OF LOS ANGELES, CALIFORNIA.

DESIGN FOR A SPECTACLE OR EYEGLASS TEMPLE.

SPECIFICATION forming part of Design No. 27,851, dated November 16, 1897.

Application filed May 17, 1897. Serial No. 636,995. Term of patent 14 years.

To all whom it may concern:

Be it known that I, SIEGFRIED G. MARSHUTZ, a citizen of the United States, residing at Los Angeles, in the county of Los Angeles and State of California, have invented and produced a new and original Design for Spectacle and Eyeglass Temples, of which the following is a specification, reference being had to the accompanying drawings, showing the same.

Figure 1 is a perspective outline view of a spectacle and eyeglass temple, showing my design. Fig. 2 is a plan of the same.

My new design for spectacle and eyeglass temples consists of a stem S, having at one end a conical body A. This conical body may be solid or hollow and may be provided with the rounded portion a at the base.

a' indicates the apex of the body, to which apex the temple-stem is attached.

The form of stem may be varied without altering the character of the design.

The characteristic features of the design for spectacle and eyeglass temples are the temple-stem and the conical body at the end of the stem.

What I claim is—

The design for spectacle and eyeglass temples substantially as shown and described.

SIEGFRIED G. MARSHUTZ.
